UNITED STATES PATENT OFFICE.

HARRY K. COLLINS, SR., OF VANDERGRIFT, PENNSYLVANIA.

POLISHING AND GRINDING DEVICE FOR ROLLS.

1,086,806.

Specification of Letters Patent.

Patented Feb. 10, 1914.

Application filed February 10, 1913. Serial No. 647,446.

To all whom it may concern:

Be it known that I, HARRY K. COLLINS, Sr., a citizen of the United States of America, residing at Vandergrift, in the county 5 of Westmoreland and State of Pennsylvania, have invented certain new and useful Improvements in Polishing and Grinding Devices for Rolls, of which the following is a specification, reference being had therein 10 to the accompanying drawing.

This invention relates to a polishing and grinding device for rolls, and the primary object of my invention is to furnish roll 15 housings with positive and reliable means, as hereinafter set forth, for expeditiously and economically grinding and polishing rolls without interfering with the use and operation of said rolls and the purposes for which they are employed.

Another object of this invention is to 20 provide a roll polishing and grinding device that can be advantageously used in connection with rolls of sheet and tin plate mills, where the rolls require considerable 25 attention on account of scale and foreign matter accumulating thereon that is detrimental to the production of a high grade product.

A further object of this invention is to 30 furnish roll housings with a novel feeding mechanism for moving a piece of cleansing or abrasive material longitudinally of the periphery of the roll while the same is in 35 operation, the feeding mechanism being positioned so as not to interfere with the rolling of metal.

A still further object of this invention is to 40 accomplish the above results by a mechanical construction that is simple, durable, inexpensive to manufacture, easy to install, and highly efficient in connection with 45 various types of rolls.

With the above and other objects in view the invention resides in a novel construction, combination and arrangement of parts 45 to be hereinafter specifically described and then claimed.

Reference will now be had to the drawings, wherein:

Figure 1 is a vertical sectional view of 50 the device in connection with a roll housing, Fig. 2 is a plan of the same partly broken away, Fig. 3 is a perspective view of a detached device, Fig. 4 is a plan of the same 55 partly broken away, Fig. 5 is a similar view of a portion of the device as applied to a

housing, Fig. 6 is a front elevation of a portion of the device, and Fig. 7 is a plan of the same.

Further describing my invention in detail with reference to the accompanying drawings, wherein like numerals denote corresponding parts throughout: 1 denotes housings of the ordinary and well known type that adjustably support revoluble rolls 65 2 and 3 forming a pass 4 for metal, as tin plate. The housings 1 are provided with vertical slots 5 and arranged in said slots are spacer blocks 6, liners 7 and transverse supports 8. The transverse supports 8 are 70 employed for holding a fore-plate 9 and a catcher's rigging 10, both of which rest upon cleats 11 provided therefor upon the inner and confronting faces of the housings 1. The fore-plate 9 permits of a sheet of metal 75 being extended into the pass 4 to be operated upon by the roll 2 and the catcher's rigging 10 guides the rolled piece of material to an operator whereby it can be shifted over the roll 2 to again pass between the 80 rolls.

12 denotes an angle plate provided with a longitudinal slot 13 and an angularly disposed ledge or tray 14 that extends the entire length of the angle plate. The ends 85 of the angle plate are provided with bearings 15 for a longitudinal screw 16 that has an end thereof provided with a beveled gear wheel 17 meshing with a similar wheel 18 mounted upon a rotatable shaft 19 journaled in the outer wall 20 of the angle plate. The shaft 19 has a shank 21 whereby a lever, wheel or other device can be placed upon the shaft to impart movement thereto and to the screw 16.

22 denotes a block that is adjustable upon the angle plate 12 through the medium of the screw 16 which extends through said block. The block 22 has a depending tongue 23 extending into the slot 13 and the bottom of said block has grooves 24 to receive longitudinal guide ribs 25, carried by the angle plate 12. In consequence of this arrangement the block 22 is moved longitudinally of the angle plate when the screw 16 105 is revolved.

26 denotes holders secured to the block 22 and arranged in said holders is a piece of abrasive grinding and polishing material 27, for instance, emery stone.

The ends of the angle plate 12 are provided with extensions 28 and 29 that ex-

tend into the slots 5 of the housings 1. The extension 28 is permanent and the extension 29 is shiftable in order that the angle plate 12 can be easily placed between said 5 housings. The shiftable extension 29 is held in brackets 30 and 31 carried by the bottom of the angle plate 12 and this particular extension has a flat spring 32 that engages the bracket 31 and locks the extension 29 in a 10 shifted position.

33 denotes an inclined deflector casing that is located upon the angle plate 12 to extend in proximity to one of the rolls, and the deflector casing associated with the roll 15 2 serves to guide a piece of metal as it passes back over the roll.

34 denotes pivoted levers carried by the confronting sides of the housings and operable against racks 35 that hold said levers 20 in adjusted position. The levers 34 are provided with coiled compression springs 36 that bear against the wall 20 of the angle plate 12 and by shifting said levers the tension of the springs 36 can be increased or decreased. The springs 36 are employed for holding the angle plates whereby the abrasive material 27 will frictionally engage the peripheries of the rolls 2 and 3. This is 25 accomplished by having the extensions 28 and 29 loosely fitting in the slots 5.

As the rolls 2 and 3 are revolved the abrasive material 27 removes scale and foreign matter from the peripheries of said rolls and the removed matter is collected by 35 the tray 14 on the device on the roll 2, while it is not necessary to use a tray in connection with the device of the roll 3. The tray 14 associated with the roll 2 prevents foreign matter from collecting upon the fore-

plate. It is thought that the manner of 40 moving the abrasive material longitudinally of the rolls will be apparent without further description and while in the drawings there is illustrated a preferred embodiment of my invention, it is to be understood that the structural elements are susceptible to such changes, as in the size, shape and manner of assemblage as fall within the scope of the appended claims. 45

What I claim is:—

1. In a roll grinding and polishing device, housings, rolls journaled in said housings, an angle plate adjustably supported between said housings, a tray carried by said plate, a block movable longitudinally of said plate, abrasive material carried by said block, a deflector arranged upon said plate, and means carried by said plate for moving said block longitudinally of said plate. 50

2. In a roll grinding and polishing device, housings, rolls journaled in said housings, an angle plate adjustably supported between said housings, a tray carried by said plate, a block movable longitudinally of said plate, abrasive material carried by said block, a deflector arranged upon said plate, means carried by said plate for moving said block longitudinally of said plate, and means carried by said housings and engaging said plate for holding the abrasive 55 material thereof in engagement with a roll. 60

In testimony whereof I affix my signature in the presence of two witnesses.

HARRY K. COLLINS, Sr.
